UNITED STATES PATENT OFFICE.

HUBERT LONGAUER, OF NORTH MILWAUKEE, WISCONSIN.

EXTERMINATOR.

Application filed March 26, 1927. Serial No. 178,622.

This invention relates to certain new and useful improvements in exterminators of the type adapted to be drawn past growing plants and vines and having means for extracting bugs, insects, and other parasites therefrom onto a collector and from there conveyed to crushing or other destroying means.

In my Letters Patent numbers 1,239,799 and 1,264,194, issued the 11th day of September, 1917 and the 30th day of April, 1918, respectively, exterminators of a character similar to the one forming the subject matter of this application are shown and described. The exterminators of said Letters Patent, however though successful in operation, are open to several objections among which may be noted their numerous parts and excessive weight, and the consequent high cost of production, that the same are capable of handling but a single row of plants at one time and further, require more than one horse or other draft animal to draw the same.

It is a further object of this invention to greatly improve and simplify the construction of exterminators of the character described and to increase their efficiency whereby twice the amount of work can be accomplished at a reduced cost of operation, in that but a single draft animal is required to pull the same.

Another object of this invention resides in the provision of an improved exterminator of the character described, the construction of which is so simplified and flexible that the handling thereof is comparatively easy and at the same time the operation thereof is very reliable.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side view, partly in elevation and partly in section, of an exterminator

embodying my invention, said view being through Figure 3 on the plane of the line 1-1;

Figure 2 is a transverse sectional view, with parts in elevation, taken through Figure 1 on the plane of the line 2-2 and looking toward the forward portion of the machine;

Figure 3 is a view, partly in section and partly in elevation, and taken transversely through Figure 1 on the plane of the line 3-3 and looking toward the rearward portion of the machine;

Figure 4 is a view, partly in section and partly in elevation, and with parts of the mechanism removed or broken away, taken transversely through Figure 2 on the plane of the line 4-4;

Figure 5 is a fragmentary view, partly in section and partly in side elevation, of the bug scraper or conveyer and crushing means, said view being taken through Figure 3 on the plane of the line 5-5;

Figure 6 is a fragmentary view in top elevation of the conveyer elevating control mechanism, said view being taken through Figure 5 on the plane of the line 6-6;

Figure 7 is a fragmentary perspective view illustrating the manner of supporting the forward portion of the main frame from the secondary frame to facilitate the hitching of a draft animal to the device, and

Figure 8 is a top plan view of the exterminator.

Referring now more particularly to the accompanying drawings, in which like numerals designate like parts throughout the several views, 5 designates a main frame mounted to travel upon wheels 6 and 7 and which may be drawn or propelled by a single draft animal or a tractor mechanism of any suitable type. The frame 5 broadly consists of two side sills or beams 8 preferably formed of angle iron and having one end directed downwardly to form vertical legs 9 which are connected at their ends by an axle 10 projecting beyond the frame to mount the wheels 6 and 7. The beams 8 are connected at their rearmost ends adjacent the legs 9 by a tie or brace member 11 on

which is centrally mounted a pair of vertical, upwardly extended, spaced guides or standards 12 which are braced from the outer ends of the main frame by diagonal braces 13 secured to the tops thereof, a guide pulley 14 being journaled between the

guides 12 at their upper ends for the purpose later described.

A pair of spaced standards 15, substantially complementary to the guides 12 and in longitudinal alignment therewith, are mounted adjacent the forward end of the main frame and have their lower end portions directed laterally, as at 16, and secured to the beams 8, as at 17, the standards 15 with their lateral members 16 being preferably formed from a single length of strap metal bent to form. The guides 12 are likewise formed from a single length of strap metal. As it is essential that the space between the guides 15 be open at the bottom, the lateral end portions 16 thereof are of necessity relatively long and to provide the proper rigidity for the guides, a pair of diagonal braces 18 are extended from their upper ends to the beams 8, to which they are secured by the means 17, and additional diagonal braces 19 extend from the upper portions of the guides to a transverse beam 20 connecting the beams 8 adjacent their forward ends and with which the usual draw bar 21 is connected by a pin 22, sills 23 being suitably secured to the forward portions of the beams 8 extended beyond the transverse beam 20. The guides 12 and 15 are further braced and held in their proper spaced relation by a connecting strap or brace 24 secured to the tops thereof as best shown in Figure 1.

The structure described above constitutes the main frame of the exterminator in which a secondary frame, carrying the bug collecting and exterminating mechanism proper, is adjustably mounted, said secondary frame consisting of a substantially diamond shaped structure 25 formed of two side members or sills bent to shape and having their forward ends connected to a pair of spaced vertical members 26 forming guides adapted to move into the space between the guide members 15 of the main frame. The lower ends of the vertical members 26 are inclined downwardly and outwardly, as at 27, to mount the supporting beams or sills of the bug conveying and crushing mechanism, the members 26 preferably being formed from a length of strap metal extending beneath the beams 28. The rear ends of the side members of the diamond shaped frame 25 are secured to a pair of vertical suspension members 29 preferably formed in one piece and extending under the beams 28 to support the rear thereof. The upper ends of the members 29 are secured to the ends of the side members of the frame 25, as at 30, and are connected by a pair of brace members 31 having their inner ends directed upwardly, as at 32, to receive the rear end of a medial brace 33 therebetween, the forward end of which is secured between the guides 26 at their upper ends. An attaching hook

34 is secured between the vertical braces 32 above the brace 33 to receive the end 35 of a lifting chain or cable 36 which is trained over the pulley 14 and has its end 37 connected with the end 38 of a lever 39. An attaching hook 40 is secured between the forward guides 26 and has the end 41 of a chain or cable 42 connected therewith which extends upwardly and is trained over a guide or pulley 43 journaled between the forward main frame guides 15 and then rearwardly being trained over the rear guide pulley 14 with its end 44 secured to the end 38 of the lever 39.

The secondary frame is braced at its forward end by a diagonal guide 45 having its upper end connected, as at 46, with the central brace member 33 and its lower end connected at 47 between the forward guides 26, said diagonal brace being preferably integral with the attaching hook 40. The rear portion of the frame is braced by diagonal members 48 connected at their lower ends to the vertical members 29 and at their upper ends to the side members of the frame 25.

Connecting the sides of the frame 25 at its widest or central point is a transverse support member 49 the ends of which are directed downwardly and secured to the frame at 50, said transverse member having two sets or series of apertures 51 therein to adjustably mount a pair of bearing members 52, the securing screws 53 of which pass through the apertures giving the bearing members the desired adjustment. A pair of horizontal, axially aligned shafts 54 are journaled, one in each bearing member 52, the outer ends of the shafts having bevel gears 55 fixed thereon meshing with gears 56 fixed to the adjacent ends of a pair of vertical shafts 57, the upper ends of which are journaled in the bearing members 52 as best illustrated in Figure 2, and the lower ends of which have spiders 58 adjustably mounted thereon, as later described. The shafts 54 are adjustably connected by a tubular shaft 59 in which their adjacent ends are adjustably secured by bolts or other means 60 so that the gears 55 are driven in unison from a sprocket member 61 fixed on the tubular shaft 59 and adapted to be driven from the wheels 6 and 7 in the manner later described. The spiders 58 each have a plurality of laterally extended arms 62 on the outer ends of which brooms or brushing members 63 are secured, the present embodiment illustrating the mounting of four brushing members from each spider 58. The adjustable mounting of the spiders 58 on their respective shafts permits the brushes to be raised or lowered according to the size of the plants.

The sprocket member 61 derives its driving power from a shaft 64 carried by the main frame and extended transversely there-

- of with its end portions journaled in bearings 65 secured to diagonal braces 66 connecting the vertical legs and horizontal beams of the main frame; the shaft 64 in 5 turn being driven from the wheels 6 and 7 through sprocket wheels 67 freely journaled on said shaft connected with driver sprockets 68 in drive connection with the wheels through a sprocket chain 69. The shaft 64 is 10 adapted to be drivingly connected or disconnected from the driven sprocket wheels 67 through clutch members 70 fixed thereon, the sprocket wheels being engaged or disengaged from the clutch members by operating levers 15 71 which are engageable behind stops 72 (see Figure 4) to hold the same in engagement with the clutch members against the action of springs 73 which normally tend to disconnect and render the drive inoperative. 20 The shaft 64 is drivingly connected with the shaft of the bevel pinions 55 by a sprocket chain 74 trained about a sprocket wheel 75 fixed to the shaft 64 and the sprocket wheel 61, there being a novel slack adjustor for 25 the chain 74 to automatically lengthen or shorten the chain 74 as the secondary frame is raised or lowered, respectively. Thus it will be seen that with the clutch members 70 in operative connection with 30 their sprockets 67, the brooms or brushing members 63 are rotated to advance inwardly at the forward part of the machine and reaching out beyond the machine in the manner illustrated in Figure 2 brushing the 35 plants or vines, as indicated at 76, and knocking the bugs and other parasites therefrom onto a collector, to be later described, which in turn conveys the bugs to a crushing means. 40 As stated above, the conveyer is mounted from the lower portion of the secondary frame and its frame is formed by the angle members 28 together with the transversely extended portions of the members 26 and 45 29, and consists of a plate 77 connecting the angle members 28 over which the conveying mechanism proper works. The conveying mechanism proper includes a pair of spaced, horizontal rods 78 having their rear portions 50 bent upwardly, horizontally and then downwardly, as at 79, to accommodate a crushing roller 80, to be later described, and on which a series of sleeves or bushings 81 are secured to form spacing members for a 55 plurality of scrapers 82 supported from the rods, a screen or other foraminous member 83 being suitably secured to the top of the scraping members, for the purpose later described. 60 The rear ends of the rods 78 are secured at 84 to a scraper 85 working rearwardly of the crusher 80 and to a pair of suspending links 86, the upper ends of which are apertured to slidably receive a pair of lifting 65 levers 87 fixed to a cross bar 88 connected at 89 with the vertical portions of a pair of right angled bearing members 90 having their horizontal portions journaled in bracket members 91 fixed to a transverse strap 92 having its ends fixed to bearings 93 in 70 which the trunnions 94 of the crusher 80 are journaled. From this, it will be seen that the rear end of the conveying scraper is supported from the roller 80 and may be raised and lowered by pivotal movement of 75 the bearing members 90 to raise and lower the free ends of the levers 87. The forward ends of the rods 78, and consequently the scraping mechanism, are supported from the forward end of the frame 80 25 by a pair of suspension rods 95 having their upper ends adjustable, as at 96, in a bracket member 97 pivoted to the frame 25 and their lower ends connected to a transverse rod or shaft 98 to which is secured 85 a pair of bell cranks 99 having the outer ends of their horizontal arms 100 pivotally connected at 101 with one of the forward scrapers 82 and the outer ends of their vertical arms 102 adjustably connected at 103 90 with a transversely disposed angle iron member 104, whereby the rocking of the bell cranks 99 to lower their arms 100 lowers the forward end of the scraping mechanism to engagement with the plate 77 and raising 95 thereof elevates the scrapers from contact with the plate 77. A connection between the angle iron member 104 and the transverse member 88 operates the levers 87 in unison with the bell cranks 99 so that the scraping 100 mechanism is elevated and lowered horizontally to cause the scrapers 82 to simultaneously engage and disengage the plate 77, the connection being made by a rod or link 105 connected at its rear end with the transverse member 88, as at 106, and having its forward end passed through an aperture in the angle iron 104 with stops 107 on opposite sides thereof to afford a certain amount of lost motion to accommodate the 105 excess movement of the vertical arms of the bell cranks 99 which are longer than those of the bearing members 90. The bearing members 90 and the bell cranks 99 thus afford means for simultaneously raising and lowering both ends of the conveying scrapers and means are operable from the drive shaft 64 to reciprocate the scrapers and elevate the same when they reach their rearmost limit of movement 110 and lower them into engagement with the plate 77 when they reach their forward limit of movement. 115 The reciprocation of the scrapers is effected through an eccentric 108 fixed to the shaft 64 and with which the rear end of a pitman 109 is connected by a ring 110, the pitman having its forward end connected, as at 111, with a transverse bolt or pivot 112 passed through the upper end of a vertical 120 130

member or upright 113 carried by a bearing member 114 journaled on the shaft 98. A brace rod 115 is connected with the upright 113 at an intermediate point and extends rearwardly having its rear end fixed to a bracket member 116 mounted on the transverse member 92 so that, as the pitman 109 is moved forwardly by rotation of eccentric 108, the roller and conveying mechanism is likewise shifted forward and vice versa. Mounted on the shaft 64 and adjustably fixed with respect to the eccentric 108 is an eccentric 117 having a greater throw than the eccentric 108 and set in advance thereof and about which a strap or ring 118 is rotatable, a pitman 119 being connected with the ring 118 the forward end of which is slideable in an aperture in the angle iron 104 and has a stop 120 thereon rearwardly of the angle iron and between which and the angle iron an expansil spring is confined. The setting of the eccentrics 108 and 117 with respect to each other is such that when the eccentric 108 causes the conveying mechanism to reach its forward limit of movement, the eccentric 117 has retracted its pitman 119 to permit the conveying scrapers to drop onto the plate 77, the conveyer and crushing member 80 being then moved rearwardly. As the conveyer mechanism reaches its rearmost limit of movement, the eccentric 117 advances its pitman 119 moving the angle iron 104 forwardly, with respect to the conveyer, elevating the free ends of the lever 87 and the arms 100 of the bell cranks 99 to raise the conveying scrapers 82 prior to the time the eccentric 108 moves its pitman 109 forward in retrieving movement.

A seat 121 is supported from the rear portion of the main frame juxtapose an operating lever 122 working in a quadrant 123 for actuating the lever 39 which effects the adjustment of the secondary frame in the main frame, a suitable detent 124 working on the quadrant to permit the setting of the secondary frame in any position.

When the secondary frame is down, a pin 125, (see Figure 7) may be inserted across the guides 15 above the upper end of the guide members 26 to hold the sills 23 in approximately horizontal position and facilitate harnessing of a draft animal in place, after which the pin 125 is removed and inserted in an opening 126 in the transverse portion 16 of one guide member 15. The secondary frame is then adjusted to any desired position by the lever 122 assisted by a spring 127 which normally exerts a tension to help support the weight of the secondary frame in the main frame.

The device is then drawn between adjacent rows of plants 76 with plant or vine guards 128 serving as guides and riding under any vines or plants which may have fallen to raise them to a position where the

brushes may properly engage the same. Each guard 128 includes a horizontal bar 129 pivotally supported from the angle members 28 by toggles 130 which normally incline rearwardly so that an upward pull on the forward end of the guard collapses the same against the adjacent members 28, there being a guard rod 131 extending rearwardly therefrom to assist in raising fallen vines.

Connected with the forward end of each vine guard at 132 is a control rod 133 which is adjustably and pivotally connected, as at 134, with the forward end of a lever 135 medially pivoted on the tubular shaft 59 adjacent the sprocket wheel 61. The rear end of lever 135 carries a pair of spaced guide pulleys 136 and 137 over which the sprocket chain 74 is trained, a contractil spring 138 connected, as at 139, with the rear end portion of the lever 135 and with the main frame, as at 140, normally maintains the chain 74 taut and tends to extend the rod 133 to position the vine guard in lowered or active position. As the secondary frame is raised by the manual operation of the lever 122 and the mechanism controlled thereby and previously described, the distance between the shafts 64 and 59 increases causing the lever 135 to pivot and assume the position illustrated in Figure 4 exerting a pull on the rod 133 and drawing the vine guard to inactive position as illustrated. In this position, the device may be readily maneuvered and turned around without interference with the plants, etc.

With the machine in active position, as illustrated in Figure 2, and the same advanced, the brooms or brushing members are rotated, in the manner described, striking the plants 76, brushing the bugs and other foreign matter therefrom and impelling the same onto the screen 83, the bugs falling through the screen which is of a mesh to prevent twigs, stones and other foreign matter from falling therethrough. A central partition wall or plate 141 extends centrally of the conveyer as best illustrated in figures 1, 2 and 4 to prevent the bugs and other matter being thrown past the conveyer due to excessive force from the brushing members, plates 142 extend from the inclined sides 27 of the vertical members 26 to a point 143 to act as a plow and prevent throwing of the bugs outwardly of the machine, and plates 144 are provided at the rear portion of the conveyer to further guard against overshooting of the bugs. The partition 141 is cut away at its forward end at 145 to accommodate the longitudinal shifting of the conveyer and the mechanism for supporting the forward end thereof and this cut away portion is adapted to be closed by a plate 146 fixed to the rod 105 to reciprocate with the conveyer.

As the bugs drop onto the plate 77, the

scraping blades 83 advance them step by step toward the crushing roller 80 and on the forward movement thereof crushes the bugs advanced by the rearmost blades 83 and 5 the bugs crushed thereby are moved rearwardly ahead of the roller on the next stroke thereof by the scraper 85, matter tending to adhere to the crushing roller being removed therefrom by a scraper 147. Thus it will be 10 seen that the scraper 85 clears the path in back of the crushing member as the crushing member kills the bugs previously placed in its path by the last scraper 82 and at the same time the last scraper 82 is conveying a 15 fresh supply of bugs toward the crushing member to be crushed as it advances on the next stroke.

From the foregoing description taken in connection with the accompanying drawings, 20 it will be readily apparent to those skilled in the art to which an invention of the character described appertains that I provide a greatly improved exterminator of the character described which is adjustable to permit the use of the device with rows of various widths, which will handle two rows of plants where heretofore only one could be handled, which is of simplified structure, reducing its cost of construction and its weight, 25 and facilitating its handling and which may be very conveniently handled by a single draft animal where heretofore more than one has been necessary.

What I claim as my invention is:

- 35 1. In an exterminator, a plate onto which insects are deposited, crushing means, conveying scrapers, and means whereby the scrapers convey the insects on the plate to the crushing means.
- 40 2. In an exterminator, a collecting plate on which insects are swept from plants and the like, a crushing roller operable on one end of the collecting plate, conveying scrapers, means mounting the scrapers for reciprocating movement over the collecting plate, means reciprocating the crushing roller as the scrapers are reciprocated, and means for maintaining the scrapers out of engagement with the collecting plate during 45 their movement in one direction.
- 50 3. In an exterminator, a collector plate, a transverse shaft supported above the plate, a lever carried by the shaft, a conveying mechanism, means connecting the free end of said lever with the adjacent end portion of the conveying mechanism, a lever pivotally mounted adjacent the other end portion of the mechanism and connected therewith, means for reciprocating the conveying mechanism over the collector plate, and means connected with said levers to actuate the same and elevate the conveying mechanism during its movement in one direction, a crushing roller movable with the conveying mechanism and toward which insects are fed by said mechanism, means for brushing insects onto the collector plate, and a baffle plate preventing said last-mentioned means from brushing the insects beyond the collecting plate.
- 55 4. In an exterminator, a collector plate, a transverse shaft supported above the plate, 60 means connecting the free end of said lever with the adjacent end portion of the conveying mechanism, a lever pivotally mounted adjacent the other end portion of the mechanism and connected therewith, means for reciprocating the conveying mechanism over the collector plate, and means connected with said levers to actuate the same and elevate the conveying mechanism during its movement in one direction.
- 65 5. In an exterminator, a collector plate, a transverse shaft supported above the plate, 65 a lever carried by the shaft, a conveying mechanism, means connecting the free end of said lever with the adjacent end portion of the conveying mechanism, a lever pivotally mounted adjacent the other end portion of the mechanism and connected therewith, means for reciprocating the conveying mechanism over the collector plate, a rod connecting said levers, and means for rotating said shaft to elevate the conveying mechanism.
- 70 6. In an exterminator, a collector plate, a transverse shaft supported above the plate, a lever carried by the shaft, a conveying mechanism, means connecting the free end of said lever with the adjacent end portion of the conveying mechanism, a lever pivotally mounted adjacent the other end portion of the mechanism and connected therewith, means for reciprocating the conveying mechanism over the collector plate, means connected with the levers to actuate the same and elevate the conveying mechanism during its movement in one direction, and a crushing roller movable with the conveying mechanism and toward which insects are fed by said mechanism.
- 75 7. In an exterminator, a collector plate, a transverse shaft supported above the plate, a lever carried by the shaft, a conveying mechanism, means connecting the free end of the lever with the adjacent end portion of the conveying mechanism, a lever pivotally mounted adjacent the other end portion of the mechanism and connected therewith, means for reciprocating the conveying mechanism over the collector plate, means connected with said levers to actuate the same and elevate the conveying mechanism during its movement in one direction, a crushing roller movable with the conveying mechanism and toward which insects are fed by said mechanism, and means for brushing insects onto the collector plate.
- 80 8. In an exterminator, a wheeled frame adapted to be drawn between rows of plants,

vines and the like, means projected from opposite sides of the frame to engage the plants of adjacent rows and remove insects therefrom, insect killing means carried by the frame, a baffle plate extended downwardly centrally of the killing means and against which the insects are thrown by said first means to drop onto the collecting means, said killing means including a reciprocating frame, and conveying means for progressing the insects to the killing means.

9. In an exterminator, a wheeled main frame adapted to be moved between rows of plants, a secondary frame vertically adjustable in the main frame, a collapsible plant guard supported from the secondary frame, means for elevating the secondary frame in the main frame to an inactive position, and means operable upon elevation of the secondary frame to collapse the plant guard.

10. In an exterminator, a wheeled main frame adapted to be moved between rows of plants, a secondary frame vertically adjustable in the main frame, a collapsible plant guard supported from the secondary frame, means for elevating the secondary frame in the main frame to an inactive position, insect removing means carried by the secondary frame, a chain and sprocket drive for said insect removing means and connected with one of the main frame wheels, chain tightening means operable to maintain the chain taut as the secondary frame is ad-

justed in the main frame, a collapsible plant guard carried by the secondary frame, and a connection between the plant guard and the chain tightening means whereby the guard is collapsed by the elevating of the secondary frame.

11. In an exterminator, a collector plate, means for brushing insects onto the collector plate, a crushing roller, means for reciprocating the crushing roller to crush the insects between it and the collector plate, and means for conveying the insects on the collector plate to the crushing roller.

12. In an exterminator, a collector plate, means for brushing insects onto the collector plate, a crushing roller, means for reciprocating the crushing roller to crush the insects between it and the collector plate, means for conveying the insects on the collector plate to the crushing roller, and means for removing the crushed insects.

13. In an exterminator, a wheeled main frame adapted to be moved between rows of plants, a secondary frame adjustable in the main frame, brushing means, a plant guard, and means connecting the plant guard with the secondary frame, whereby it is free to ride on the ground to raise plants adjacent thereto into the path of the brushing means when the secondary frame is in operative position.

In testimony whereof I hereunto affix my signature.

HUBERT LONGAUER.
